CENTRALIZED TRAFFIC CONTROLLING
SYSTEM FOR RAILROADSDarrol F. De Long, Charlotte, N. C., assignor to
General Railway Signal Company, Rochester,
N. Y.

Application August 29, 1936, Serial No. 98,611

14 Claims. (Cl. 246—3)

This invention relates to centralized traffic controlling systems for railroads and it more particularly pertains to a means for registering controls in a communication system of the multiple impulse or code type.

In the multiple impulse or code type communication system commonly employed in centralized traffic control systems for the purpose of governing the operation of switches and signals at a distant field station from a central control office, the controls for governing the operation of the switches and signals are transmitted by a series of time spaced positive or negative impulses, or impulses otherwise characterized by variable line circuit conditions or the like. These characteristic control impulses are employed to condition suitable relays at the field station for governing the operation of power operated track switches and for governing operation of their associated signals.

In one arrangement, such as disclosed for example in the prior application of Preston et al. Ser. No. 455,304, filed May 24, 1930, corresponding to Australian Patent No. 1501 of 1931, the character of the control impulse for each step is registered by operating a two-position polarized relay to one position or the other, the armature of this relay, conveniently termed a mag-stick relay, being magnetically held in the position to which it is set until changed by some subsequent impulse. In such an arrangement a control impulse which is for the purpose of operating the mag-stick relay from its existing position to another desired position may not be effective, due to a broken wire, a bad connection or the like, with the result that the desired control actually transmitted and received at the field station is not properly registered. Although the system for controlling the switches and signals is so organized that no unsafe condition is produced by such failure, trains may be signalled to advance over a route not desired by the operator.

Another arrangement for registering control impulses is disclosed in the prior application of R. F. Wells, Ser. No. 634,370, filed September 22, 1932, in which neutral decoding relays, all de-energized at the beginning of a transmitting cycle, are selectively energized in accordance with the control code transmitted and then the relays which control the switches and the signals are conditioned, provided the decoding relays have properly responded to the control code transmitted. This arrangement requires a pair of decoding relays for each step in addition to the switch and signal control relays.

One object of this invention is to provide means for registering the code character of the control impulses, which is reliable in its operation but does not require the use of such additional decoding means for each step.

Generally speaking, by way of explanation and without attempting to define the nature or scope of the present invention, it is proposed to employ neutral stick control relays directly responding in succession to the code character of the control impulses for the successive steps, these relays individually or jointly controlling the operation of the switches and signals; and to so control these control relays that they are normally deenergized, being selectively energized by the received code impulses by means of their pick-up circuits and having their pick-up and stick circuits so arranged that adequate wrong route protection is provided.

Other characteristic features and advantages of the organization of relays and circuits constituting the present invention will be in part apparent and in part pointed out as the description progresses.

The present invention relates to only a part of a complete system of code communication for centralized traffic control. While it is contemplated that the invention will be used with the various features commonly employed or suitable for such a complete communication system, such as station selection, transmission of indications and the like, in order to simplify the disclosure and the explanation of the present invention, such features of the complete system are not illustrated and will not be described, except in a general way and insofar as appears to be necessary to understand the functions and mode of operation of the parts and circuits constituting this particular improvement.

In the accompanying drawings, Figs. 1 and 1A, with Fig. 1A placed to the right of Fig. 1 and with correspondingly identified lines in alignment, diagrammatically illustrate the circuit arrangement of the present invention. For the purpose of simplifying the drawings and facilitating in the explanation the various relays and circuits have been shown diagrammatically and conventionally and the symbols (+) and (—) have been employed to indicate connections to the opposite terminals of a battery or other suitable source of current, instead of showing all of the wiring connections that would be employed in practice.

Referring to Fig. 1, the central control office of the system is indicated by means of the dotted

5

55

rectangle in the upper left-hand corner. The code transmitting and code receiving equipment in the control office is connected to the equipment at the various field stations by three line 5 wires, comprising a stepping and control line wire 10, an indication line wire 12, and a common return wire 14. The stepping and control line wire 10, together with common return wire 14, constitutes a stepping and control line circuit 10 which is energized in the control office with a series of impulses of selected polarity for operating stepping relays at the field station sequentially one at a time and for conditioning control relays at the station for governing the operation 15 of switches, signals and the like.

For the purpose of explaining and understanding the purpose of the present improvement, it is considered unnecessary to illustrate the code transmitting equipment in the control office, by 20 means of which these series of impulses are applied to the stepping and control line circuit in accordance with the code call for the selection of a particular station and in accordance with the controls to be transmitted, as determined by the 25 positions of switch and signal levers manually set by the operator for the purpose of controlling the operation of corresponding switch machines and signals.

It is contemplated that the controls for a power 30 operated switch or switches and associated signals will be transmitted as a group to each of the various stations, one station at a time as the operator positions the switch and signal levers for these stations and actuates corresponding starting buttons, all in the manner disclosed in the above-mentioned application of Preston et al. Ser. No. 455,304, or in the manner disclosed in the prior application of Bushnell et al., Ser. No. 640,062 filed October 28, 1932, corresponding to 35 British Patent 419,399.

It is further contemplated that the controls for a plurality of switches or for various routes 40 may be transmitted, either simultaneously during the same operating cycle or successively on 45 different operating cycles as best adapted to the particular track layout. For the purpose of explaining the nature of the present invention, the various ways of transmitting controls to several control stations for various track layouts 50 may be disregarded and for the purpose of a sufficient understanding of the present invention it is sufficient to consider that it is applied to a single switch and its associated signals at one field location.

The transmission of indications, station selection, the arrangement and groups of switch and signal controls and other features characteristic 55 of a complete system incorporating the present improvement will be disregarded and this improvement will be considered in its simplest form. Accordingly, included in the field station apparatus is a three-position biased to neutral polar line relay F connected in the stepping and control line 10. A neutral repeater line relay FP is energized each time line relay F is energized, irrespective of the polarity of energization of relay F, by means of an obvious circuit completed by contact 11. A slow-release relay SA is energized over an obvious circuit, including front contact 13 of relay FP, at the beginning of each operating cycle and is maintained energized during such cycle while line relay F and its repeater relay FP are intermittently operated.

A bank of stepping relays 1V, 2V, 3V, etc., and

including a half-step relay VP, is provided at the field station for marking off the steps of an operating cycle and although the circuits of these relays are not shown in detail it will be understood that they are operated by the intermittent operation of contact 13 by means of circuits completed through front contacts of relay SA as illustrated by contact 15. Any suitable arrangement of stepping relays may be employed, the particular bank illustrated being assumed to correspond to that disclosed in the above-mentioned prior application of Bushnell et al., Ser. No. 640,062. Since the circuit organization and mode of operation of the bank of stepping relays is explained in detail in this prior application and since its specific form constitutes no part of the present invention, it will be sufficient to point out generally certain characteristic features in the operation of the stepping relay bank.

During the conditioning period at the beginning 20 of a cycle, relays F, FP, and SA are picked up, followed by the picking up of relay VP. Relay VP is maintained energized by a stick circuit completed through back contacts of the stepping relays. When the line circuit is deenergized at the end of the conditioning period and relays F and FP are dropped, the first stepping relay 1V is energized, after which it closes a stick circuit for itself which maintains this stepping relay energized until the end of the operating cycle. While relay FP is down, relay VP is maintained energized by an additional stick circuit through a back contact of relay FP. When the line circuit is next energized, relay VP drops since relay 1V is now picked up. During 25 the next deenergization of the line circuit, stepping relay 2V is energized through a back contact of relay VP and a front contact of relay 1V; and during the next following energization of the line circuit, relay VP again picks up to prepare 30 the energizing circuit for the next stepping relay 3V. This same operation is repeated for as many steps as desired.

Thus, in accordance with the particular arrangement of stepping relays assumed for the specific embodiment of the present invention, after relay VP is initially energized during the first energization of the line circuit in the conditioning period, a stepping relay picks up during each succeeding deenergization of the line circuit. Relay VP shifts, that is changes from its energized or deenergized condition as the case may be, during each of the succeeding energized periods of the line circuit. This operation of stepping relays 1V, 2V, and 3V sequentially establishes local channel circuits for controlling control relays RA, LA, RD, LD, WN, and WR in accordance with the polarity of energization of the line relay during the next energized period of the line following the deenergized period during 45 which the corresponding stepping relay was picked up.

The relays illustrated in Fig. 1A comprise lock relay L, lock stick relay LS, signal control relay AGS, normal switch correspondence relay NWCR, reverse switch correspondence relay RWCR, switch position repeating relay WP, track relay T and track repeater relay TP. The operation and cooperation of these relays and their circuits will be brought out in the following detailed description.

With the possibility of there being either a positive or a negative impulse for each step, the number of code combinations possible equals two raised to the power of the number of steps. Each 50 55 60 65 70 75 80 85 90 95 100

one of these combinations may be used for the control of the switch and signals associated with a particular route. Since three steps have been illustrated in the present disclosure for control codes, eight different code combinations may be formed as listed in the table given below. As indicated in Fig. 1, it is convenient to refer to the channel circuits selected at the various steps as 1+ or 1- selected at the first step, 2+ or 2- selected at the second step and 3+ or 3- selected at the third step.

Table of control codes

15	Code number	First step	Second step	Third step	Code use
1		+	+	+	Not used.
2		+	+	-	Signal 1A.
3		+	-	+	Not used.
4		+	-	-	Signal 1B.
20	5	-	+	+	Signal 2A.
6		-	+	-	Stop Sw. normal.
7		-	-	+	Signal 2B.
8		-	-	-	Stop Sw. reverse.

25 May be used for call-on signal or the like.

Considering the general operation of the system, the switch control relays WN and WR are normally deenergized and one or the other is picked up on the second control step in accordance with the polarity of the impulse received on this step for every control cycle, provided lock relay L is up. The switch control relay which picks up then sticks up from energy applied to the No. 1 stick bus, including the opposite control relay down, until the end of the cycle when relay SA drops and from then on until the switch completes its stroke, this latter due to energy applied to the No. 1 stick bus through a front contact of relay LS which remains picked up until the switch does complete its stroke.

40 The switch correspondence relay corresponding to the last operated position of the switch is energized and the other correspondence relay is deenergized. These correspondence relays are picked up through front contacts of the corresponding switch control relays and through a neutral and a polar contact of the WP relay in the corresponding position. By virtue of this arrangement, when a route is cleared with the switch in the desired position, no change in position of the correspondence relays takes place. However, if it is desired to operate the switch to the opposite position, the picking up of the opposite switch control relay immediately releases the correspondence relay which is picked up for the opposite position of the switch and this in turn picks up the LS relay and initiates the movement of the switch. When the switch has completed its movement to the new position, the WP relay assumes a corresponding position and this in turn is followed by the picking up of the proper switch correspondence relay. This is then followed by the release of the LS relay, which removes energy from the switch machine and also removes energy from the No. 1 stick bus for allowing the switch control relay to drop.

45 The first control step of each control cycle picks up either the RA or the LA relay, depending upon the polarity of the impulse for this step, which constitutes the first digit of the signal control code. A stop code is obtained by picking up both relays RA and LA, however the pick-up circuits of these two relays are so interlocked that

a double impression on the first step prevents erroneously putting a signal to stop.

5 It will be noted that the stick windings of the RA and LA relays extend to (-) through back contacts of the WN and WR relays in multiple. This is for the purpose of releasing the RA or the LA relay that was picked up on the first control step, and thus cancel any signal control code, if during a cycle a double impression is received on the second or switch control step.

10 Signal control relays RD and LD are selectively picked up on the third step, provided that either relay LA or relay RA is still up and that one of the switch control relays is up. Energy is applied to the pick up windings of the RD and LD relays through front contacts of the WN and WR relays in multiple to insure that no route can be cleared unless a switch control relay has been picked up to insure the correct position of the switch as previously mentioned. Either relay RD or relay 15 LD when picked up drops lock relay L because of open back contact 70 or 83, which in turn prevents the picking up of either relay WN or relay WR and with neither WN nor WR picked up no signal control relay can be picked up to clear the 20 opposing signal.

25 Front contact 50 of relay RA is not used, but it will be understood that this contact may be used if desired to pick up another relay for the purpose of giving a call-on signal or the like.

30 Considering now the sequence of operations and assuming that the last switch control code was positive (2+) for energizing relay WN to cause the switch machine to assume its normal position, relay NWCR was picked up as a result 35 of the switch machine moving to its normal position and it remains stuck up over a circuit extending from (+), front contact 16 of relay WP, contact 17 of relay WP in its left hand position, conductor 18, back contact 19 of relay WR, conductor 93, front contact 20 and winding of relay NWCR, to (-).

35 Relay TP is normally energized over an obvious circuit closed at front contact 21 of relay T, since it is assumed that the illustrated track section is 40 unoccupied and that relay T is up. Relay AGS is normally energized over a circuit which may be traced from (+), back contacts 22 and 23 of relays RD and LD respectively, conductor 93, winding of relay AGS and front contact 24 of relay 45 TP, to (-).

45 The various routes set up and the operations which result from the reception of each code in the above code table (except the first and third which are not used) may be best understood by 50 considering each code combination individually. During the conditioning period, relays F, FP, SA, and VP are picked up and when relays F and FP are dropped, following the conditioning period, stepping relay 1V is picked up. As previously 55 pointed out the remaining stepping relays are picked up during the successive deenergized periods of the line circuit which follow each impulse, so that the polarity of the next impulse is effective to condition the control relays for that 60 step.

55 Code No. 2.—This is the code for clearing signal 65 1A and for actuating the track switch to its normal position. The (+) impulse on the first step is effective to position the polar contacts of relay F to the right for closing a pick-up circuit for relay RA which extends from (+), contact 25 of relay F in its right-hand dotted position, back contacts 26 and 27 of relays 3V and 2V respectively, front contact 28 of relay 1V, bus 1+, back 70

75

contact 29 of relay LA and upper winding of relay RA, to (-). Relay RA opens the pick-up circuit of relay LA at back contact 30 to prevent the erroneous picking up of relay LA in the event of a double impression of the first code. Relay RA closes a stick circuit for itself which extends from (+), front contact 31 of relay SA, front contact 32 and lower winding of relay RA and either back contact 33 of relay WN or back contact 34 of relay WR, to (-).

The second impulse of this code combination is (+) which picks up relay WN over a circuit which may be traced from (+), contact 25 of relay F in its right-hand dotted position, back contact 26 of relay 3V, front contact 27 of relay 2V, bus 2+, lower winding of relay WN, conductor 95, and front contact 35 of relay L, to (-). Relay WN closes a stick circuit for itself which extends from (+), front contact 36 of relay SA, No. 1 stick bus, back contact 37 of relay WR, front contact 38 and upper winding of relay WN, to (-).

The picking up of relay WN closes a circuit for operating the switch machine and the associated track switch to its normal position (if not already in this position) which extends from (+), front contact 39 of relay WN, normal conductor N, front contact 40 of relay LS (picked up for reasons to be described), switch machine operating winding, front contact 41 of relay LS, reverse conductor R and back contact 42 of relay WR, to (-).

Relay LS is picked up in response to the picking up of relay WN (if the switch machine was in its reverse position), because relay NWCR would be down under this condition and relay RWCR would be dropped because of open back contacts 43 and 44 of relay WN. The pick-up circuit for relay LS extends from (+), front contact 45 of relay TP, back contacts 46 and 47 of relays RWCR and NWCR respectively, winding of relay LS and front contact 48 of relay L, to (-). As previously mentioned, relay LS in its picked up position applies (+) energy to the No. 1 stick bus over an obvious circuit closed at its front contact 49. When the switch machine and associated track switch attain the normal locked condition, relay WP will be picked up (being de-energized while the switch machine is in operation) and its polar contacts will be positioned to the left.

A circuit is now closed for picking up relay NWCR which extends from (+), front contact 51 of relay WN, back contact 52 of relay WR, conductor 53, front contact 54 of relay WP, contact 55 of relay WP in its left-hand position and winding of relay NWCR, to (-). Relay NWCR closes the previously described stick circuit for itself. The opening of back contact 47 of relay NWCR deenergizes relay LS so that this relay drops and prevents a change in the switch machine position until a succeeding code is received.

The (-) impulse received on the third step is effective to pick up relay RD over a circuit extending from (+), contact 25 of relay F in its left-hand dotted position, front contact 56 of relay 3V, bus 3-, back contact 59 of relay LA, front contact 60 of relay RA, upper winding of relay RD and front contact 61 of relay WN, to (-). Relay RD closes a stick circuit for itself which extends from (+), front contact 62 of relay T, conductor 63, back contact 64 of relay LD, back contact 65 of relay LA, front contact 66 and lower winding of relay RD, to (-).

Signal 1A is cleared over a circuit extending from (+), front contact 67 of relay AGS, back contact 68 of relay LS, (which contact prevents the clearing of any signal until the switch reaches the desired position as indicated by the proper correspondence relay being picked up), back contact 69 of relay L (relay L being dropped when relay RD opens its back contact 70), conductor 71, back contact 72 of relay LD, front contact 73 of relay RD, conductor 74, back contact 75 of relay RWCR, front contact 76 of relay NWCR, to the 1A signal circuit. Although the detailed circuits leading to signals 1A, 1B, 2A, and 2B are not shown, it will be understood that these circuits may include such other selections and local circuit protection as desired.

Code No. 4.—The first (+) impulse received in this code combination is effective to pick up relay RA in the manner described in connection with code No. 2. The second (-) impulse picks up relay WR (instead of relay WN), over a circuit extending from (+), contact 25 of relay F in its left-hand dotted position, back contact 56 of relay 3V, front contact 57 of relay 2V, bus 2-, lower winding of relay WR, conductor 95 and front contact 35 of relay L, to (-). Relay WR is stuck up over an obvious circuit including its front contact 37 and back contact 38 of relay WN. With relay WR up and relay WN down, pole changing contacts 39 and 42 are effective to reverse the flow of current over wires R and N from that previously described so that the switch machine is operated to its reverse locked position.

Relay NWCR is deenergized because of open back contact 19 of relay WR and relay RWCR is picked up when the switch reaches its reverse locked position over a circuit extending from (+), contact 55 of relay WP in its right-hand dotted position, front contact 54 of relay WP, conductor 53, front contact 52 of relay WR, back contact 43 of relay WN, conductor 71 and winding of relay RWCR, to (-). Relay RWCR is then stuck up over a circuit extending from (+), front contact 16 of relay WP, contact 17, relay WP in its right-hand dotted position, conductor 45 78, back contact 44 of relay WN, conductor 79, front contact 80 and winding of relay RWCR, to (-). The opening of back contact 46 of relay RWCR obviously drops relay LS.

The third (-) impulse is effective to pick up relay RD in the same manner described in connection with code No. 2. Signal 1B is cleared over the previously described circuit, but which now extends through back contact 76 of relay NWCR and front contact 75 of relay RWCR.

Code No. 5.—The first (-) impulse in this code combination is effective to pick up relay LA over a circuit extending from (+), contact 25 of relay F in its left-hand dotted position, back contacts 56 and 57 of relays 3V and 2V respectively, front contact 58 of relay 1V, bus 1-, back contact 30 of relay RA and upper winding of relay LA, to (-). Relay LA closes an obvious stick circuit for itself at its front contact 81 and the opening of back contact 29 prevents the erroneous energization of relay RA on this step in the event of a double impression of impulses.

The second (+) impulse of this code combination is effective to pick up relay WN as previously described.

The third (+) impulse of this code combination is effective to pick up relay LD over a circuit extending from (+), contact 25 of relay F in its right-hand dotted position, front contact 26 of relay 3V, bus 3+, back contact 50 of relay RA,

front contact 82 of relay LA, upper winding of relay LD and front contact 61 of relay WN, to (—).

The circuit for clearing signal 2A is now completed and extends from (+), front contact 61 of relay AGS, back contact 68 of relay LS, back contact 69 of relay L (relay L is deenergized because of open back contact 83 of relay LD), conductor 71, back contact 73 of relay RD, front contact 72 of relay LD, conductor 84, back contact 85 of relay RWCR and front contact 86 of relay NWCR to the circuit leading to signal 2A.

Code No. 6.—The first (—) impulse of this code combination is effective to pick up relay LA as previously described. The second (+) impulse of this code combination is effective to pick up relay WN as previously described. This is a stop code and is due to the picking up of relay RA (with relay LA also picked up) in response to the third (—) impulse, by means of a circuit extending from (+), contact 25 of relay F in its left-hand dotted position, front contact 56 of relay 3V, bus 3—, front contact 59 of relay LA and upper winding of relay RA, to (—). (+) energy on the No. 2 stick bus is effective to stick up both relays LA and RA and because both back contacts 65 and 87 are open, the stick circuit for the RD and LD relays is incomplete so that both of these relays will be deenergized. With relays RD and LD both down the circuit is complete (including conductor 88) for picking up relay L, which prevents the clearing of any signal, due to open back contact 69. Also, since both contacts 72 and 73 of relays LD and RD, respectively, are connected to conductor 71, neither bus 74 nor 84 can be energized for clearing any of the signals.

Code No. 7.—The first (—) impulse of this code combination is effective to pick up relay LA as previously described. The second (—) impulse of this code combination is effective to pick up relay WR as previously described. The third (+) impulse of this combination is effective to pick up relay LD as previously described, except in this instance (—) is connected to the upper winding of the LD relay at front contact 89 of relay WR instead of at front contact 61 of relay WN.

Signal 2B is cleared over a circuit extending from (+), front contact 67 of relay AGS, back contact 68 of relay LS, back contact 69 of relay L, conductor 71, back contact 73 of relay RD, front contact 72 of relay LD, conductor 84, back contact 86 of relay NWCR, and front contact 85 of relay RWCR to the 2B signal circuit.

Code No. 8.—The first (—) impulse of this code combination is effective to pick up relay LA as previously described. The second (—) impulse of this code combination is effective to pick up relay WR as previously described. The third (—) impulse is effective to pick up relay RA over the circuit previously described. This is also a stop code because relays LA and RA are both picked up. Both relays RA and LA are stuck up by means of the energy applied to the No. 2 stick bus, and because both contacts 65 and 87 are open, neither relay RD nor relay LD can be energized so that no signal can be cleared.

When the train passes onto the illustrated track section, relays T and TP drop in sequence. The opening of contact 97 of relay TP maintains the L relay deenergized as long as the track is occupied. The opening of contact 24 of relay TP maintains relay AGS deenergized as long as the track section is occupied to prevent clearing any

of the signals, because of open front contact 67 of relay AGS. The opening of front contact 45 of relay TP maintains relay LS deenergized so that the position of the track switch cannot be changed as long as the illustrated track section is occupied. The opening of front contact 62 of relay T deenergizes the stick circuits for the RD and LD relays, so that the particular one of these relays which is picked up is deenergized, and the subsequent closure of back contact 92 of relay TP again applies (+) energy to conductor 63, so that relay RD or relay LD can be stuck up in the event that a subsequent code is received while the track section is occupied, so that this subsequent code can be stored.

In the above description the return to normal or the clearing out function of the system has not been considered but only the complete control operation has been outlined. After the last step has been taken the control line circuit is deenergized in the control office for a prolonged period of time, so that relays F and FP remain down long enough to allow relay SA to be dropped. The dropping of relay SA effects the deenergization of the stepping relays. The opening of front contact 36 of relay SA removes energy from the No. 1 stick bus and with relay LS deenergized the stick circuits for the WN and WR control relays are deenergized, so that the particular one of these control relays which was picked up during the cycle is dropped out at the end of the cycle. The opening of front contact 31 of relay SA likewise removes energy from the No. 2 stick bus, so that the RA and LA relays are deenergized at the end of the cycle.

Stick contact 90 on relay AGS is for the purpose of maintaining relay AGS energized as long as the track section is unoccupied, even though the pick-up circuit of this relay is opened at back contact 22 of relay RD or back contact 23 of relay LD. This maintains the signal clearing circuit complete at front contact 67 of relay AGS. When relay AGS is once dropped, due to the opening of front contact 24 of relay TP, it then requires relays RD and LD deenergized and relay TP picked up for the reenergization of relay AGS.

Having thus described a centralized traffic controlling system as one specific embodiment, it is desired to be understood that this form is selected to facilitate in the disclosure of the invention rather than to limit the number of forms which it may assume and it is further to be understood that various modifications, adaptations and alterations may be applied to the specific form shown to meet the requirements of practice without in any manner departing from the spirit or scope of the invention except as limited by the appended claims.

What I claim is:—

1. In a centralized traffic controlling system for governing signals associated with a track section located at a field station remote from a control office, a single stepping and control line circuit extending from the office to the station and energized with a plurality of polar impulses, apparatus at the station comprising, a series of stepping relays operated sequentially in response to the energization and deenergization of said line circuit irrespective of the polarity of such energization, a first pair of signal control relays each governing the clearing of either of two signals for one particular direction over a track switch in accordance with its position, a second pair of signal control relays, means governed by said stepping

relays for momentarily energizing one or the other of said first pair of signal control relays at one step depending upon the polarity of the impulse applied to said line circuit for that step, means governed by said stepping relays for momentarily energizing one or the other of said second pair of signal control relays at another step depending upon the polarity of the impulse applied to said line circuit for that step, stick circuits for maintaining said first and said second pair of signal control relays energized, means including a track relay of a track circuit adjacent said track switch for breaking the stick circuit of said first pair of signal control relays whereby they are deenergized upon the occupancy of said section, and means controlled by said second pair of signal control relays for breaking the stick circuit of said first pair of signal control relays whereby said first pair of signal control relays cannot be maintained energized when both of said second pair of signal control relays are energized.

2. In a centralized traffic controlling system for governing signals associated with a track section located at a field station remote from a control office, a control line circuit extending from the office to the station and energized with a plurality of polar impulses, a first pair of neutral stick control relays respectively governing the clearing of signals in opposite directions over said track section, a second pair of neutral stick control relays, means for momentarily energizing one or the other of said first pair of control relays depending upon the polarity of the impulse applied to said line circuit at one particular time, means for momentarily energizing one or the other of said second pair of control relays depending upon the polarity of the impulse applied to said line circuit at another particular time, a stick circuit for each of said first pair of control relays including the back contact of the other, and means including back contacts of said second pair of control relays in multiple for controlling the continuity of the stick circuits of said first pair of control relays.

3. In a centralized traffic controlling system of the multiple impulse type, a track switch and associated signals, a control line circuit, stepping relays operated sequentially in response to a series of polar impulses applied to said line circuit irrespective of their polarity, a signal control relay, means governed in accordance with the polarity of one particular impulse of said series at one particular step of said stepping relays for momentarily energizing said signal control relay, a stick circuit for said signal control relay for maintaining it energized after once momentarily energized, means controlled by a detector track circuit for breaking said stick circuit to deenergize said signal control relay upon passage of a train, and additional means controlled by impulses in said line circuit at another step of said stepping relays for breaking said stick circuit to deenergize said signal control relay.

4. In a centralized traffic controlling system of the multiple impulse type, a track switch and associated signals, a control line circuit, stepping relays operated sequentially in response to a series of polar impulses applied to said line circuit irrespective of their polarity, two neutral signal control relays, means governed in accordance with the polarity of one particular impulse of said series at one particular step of said stepping relays for momentarily and selectively energizing one of said signal control relays, stick circuits for

said signal control relays for maintaining them energized after once momentarily energized, means controlled by a detector track circuit for breaking said stick circuits to deenergize said signal control relays upon passage of a train, and additional means controlled by impulses in said line circuit at another step of said stepping relays for breaking said stick circuits to deenergize said signal control relays.

5. In a centralized traffic controlling system for railroads comprising an office and a station, means at said station for receiving a series of current impulses transmitted from said office, a track switch and a pair of switch control relays at said station, means responsive to the reception of certain of said impulses for selectively energizing one or the other of said pair of switch control relays, means controlled by the energization of said one or said other of said switch control relays for operating said track switch to normal or reverse positions respectively, a pair of opposing signals governing traffic over said switch, a first and a second pair of signal control relays at said station, a control circuit for each signal closed only when the corresponding relay of said first pair of signal control relays is energized, means effective when selected impulses are included in said series for energizing a selected relay of said first and said second pair of signal control relays, means operated by each relay of said pair of switch control relays for releasing the other relay of this pair, means operated by each relay of said first pair of signal control relays for releasing the other relay of this pair, and means operated by both relays of said second pair of signal control relays for releasing either or both relays of said first pair of signal control relays.

6. In combination with a railway switch; four signals for governing traffic over said switch; two switch control relays; means for operating said switch to one position or the other according as one or the other of said switch control relays is energized; a plurality of signal control relays; means controlled from a remote point for selecting said switch and said signal control relays; four signal circuits, one for each of said signals and each including contacts closed only when the route over the switch governed by the associated signal is available and unoccupied; means operated by each of said switch control relays when energized for completing energizing circuits for one portion of the selected signal control relays; and means operated by each of said switch control relays when deenergized for completing energizing circuits for another portion of the selected signal control relays.

7. In combination with a railway switch; four signals for governing traffic over said switch; two switch control relays; means for operating said switch to one position or the other according as one or the other of said switch control relays is energized; a plurality of signal control relays; means controlled from a remote point for selecting said switch and said signal control relays; four signal circuits, one for each of said signals and each including contacts closed only when the route over the switch governed by the associated signal is available and unoccupied; means operated by each of said switch control relays when energized for completing energizing circuits for one portion of the selected signal control relays; means operated by each of said switch control relays when deenergized for completing energizing circuits for another portion of the se-

lected signal control relays; and stick circuits for each signal control relay of said one portion controlled through back contacts of another signal control relay of said one portion.

5. In combination, a line circuit having a plurality of coded impulses applied thereto, a track switch, a signal for governing traffic over said track switch, a signal circuit for said signal, a switch control relay actuated by one of said coded impulses for governing said track switch, a correspondence relay, means controlled by said coded impulses for selecting said signal circuit, a correspondence relay, means controlled by said track switch and said switch control relay in corresponding positions for completing a pick-up circuit for said correspondence relay, means controlled by said track switch and said correspondence relay for completing a stick circuit for said correspondence relay, and means controlled by 20 said correspondence relay for completing the selected circuit for said signal.

9. In combination, a line circuit having a plurality of coded impulses applied thereto, a track switch, signals for governing traffic over said track switch, signal circuits for said signals, a switch control relay actuated by one of said coded impulses for governing said track switch, signal control relays actuated by other of said coded impulses for selecting said signal circuits, a correspondence relay, means controlled by said track switch and said switch control relay in corresponding positions for completing a pick-up circuit for said correspondence relay, means controlled by said track switch and said correspondence relay for completing a stick circuit for said correspondence relay, and means controlled by said correspondence relay for completing the selected circuits for said signals.

10. In combination, a line circuit having a plurality of coded impulses applied thereto, a track switch, signals for governing traffic over said track switch, signal circuits for said signals, a plurality of switch control relays actuated by certain of said coded impulses for governing said track switch, signal control relays actuated by other of said coded impulses for selecting said signal circuits, a plurality of correspondence relays, means controlled by said track switch and said switch control relays in corresponding positions for selectively completing pick-up circuits for said correspondence relays, means controlled by said track switch and said correspondence relays for completing stick circuits for said correspondence relays, and means controlled by said correspondence relays for completing the selected circuits for said signals.

11. In combination, a line circuit having a plurality of coded impulses applied thereto, a track switch, signals for governing traffic over said track switch, signal circuits for said signals, a plurality of switch control relays actuated by certain of said coded impulses for governing said track switch, signal control relays actuated by other of said coded impulses for selecting said signal circuits, a plurality of correspondence relays, means controlled by said track switch and said switch control relays in corresponding positions for selectively completing pick-up circuits for said correspondence relays, means controlled by said track switch and said correspondence relays for completing stick circuits for said correspondence

relays, means controlled by said correspondence relays for completing the selected circuits for said signals, and interlocking stick circuits for said signal control relays arranged to maintain one and only one of said signal control relays energized after being actuated. 5

12. In combination, a line circuit having a series of polar impulses forming a code transmitted thereover, a polar relay included in said line circuit for repeating said impulses, step-by-step mechanism operable to take one step for each of said impulses, a first pair of control relays and a second pair of control relays, circuits for said first pair of control relays prepared at one step of said mechanism and selectively energized in accordance with the polarity of the impulse transmitted at that step as repeated by said polar relay, and circuits for said second pair of control relays prepared at another step of said mechanism and selectively energized in accordance with the polarity of the impulse transmitted at that step as repeated by said polar relay only when one of said first pair of relays is energized and the other is deenergized. 10 15 20

13. In combination, a line circuit having a series of polar impulses forming a code transmitted thereover, a polar relay included in said line circuit for repeating said impulses, step-by-step mechanism operable to take one step for each of said impulses, a first pair of control relays and a second pair of control relays, circuits for said first pair of control relays prepared at one step of said mechanism and selectively energized in accordance with the polarity of the impulse transmitted at that step as repeated by said polar relay, circuits for said second pair of control relays prepared at another step of said mechanism and selectively energized in accordance with the polarity of the impulse transmitted at that step as repeated by said polar relay only when one of said first pair of relays is energized and the other is deenergized. 25 30 35

40

14. In combination, a line circuit having a series of polar impulses forming a code transmitted thereover, a polar relay included in said line circuit for repeating said impulses, step-by-step mechanism operable to take one step for each of said impulses, a first pair of control relays and a second pair of control relays, circuits for said first pair of control relays prepared at one step of said mechanism and selectively energized in accordance with polarity of the impulse transmitted at that step as repeated by said polar relay, circuits for said second pair of control relays prepared at another step of said mechanism and selectively energized in accordance with the polarity of the impulse transmitted at that step as repeated by said polar relay only when one of said first pair of relays is energized and the other is deenergized, stick circuits for said second pair of control relays completed when and only when one or the other of said first pair of control relays is deenergized, and means for sticking an energized one of said first pair of control relays as long as a series of impulses is being transmitted over said line circuit. 45 50 55 60 65
